UNITED STATES PATENT OFFICE.

BENJAMIN F. LITZENBERG, OF RUSSELL, IOWA.

SULKY-PLOW.

SPECIFICATION forming part of Letters Patent No. 224,095, dated February 3, 1880.

Application filed December 12, 1879.

To all whom it may concern:

Be it known that I, BENJAMIN F. LITZENBERG, of Russell, in the county of Lucas and State of Iowa, have invented certain new and useful Improvements in Sulky-Plows; and I do hereby declare that the following is a full, clear, and exact description of the invention, which will enable others skilled in the art to which it appertains to make and use the same, reference being had to the accompanying drawings, which form a part of this specification.

Figure 1 is a perspective view. Fig. 2 is a vertical cross-section. Fig. 3 is a top view. Fig. 4 is a side view, and Fig. 5 is a detail view of one of the sides of the frame.

Corresponding parts in the several figures are denoted by like letters of reference.

This invention relates to sulky-plows; and it consists, essentially, in the improved construction of the frame, by which the latter may be adapted either to a right or left hand plow or set of plows or to a cultivator, as will be hereinafter more fully described, and particularly pointed out in the claim.

In the annexed drawings, A A represent the sides of my improved sulky-frame. Said sides, one of which is shown in detail in Fig. 5 of the drawings, consist of suitably-proportioned straight plates, provided at each end with a square or perforation, B, and near one of the ends with a third similar opening, C. The said sides are connected by the axle D, the ends of which are passed through the upper openings, B, and secured by nuts E. A crank-axle or bail, F, is provided with spindles G G, by which it is journaled in the lower openings, B.

H H represent the stub axles or spindles, which are inserted from the outside through the middle openings, C, and secured by nuts I. J J are the transporting-wheels, which are adjusted upon the spindles.

The tongue K is bolted upon the inside of one of the side pieces, A, of the frame, and immediately below or above it is a foot bar or bail, L, similarly secured.

One of the spindles G of crank-axle F extends through the side of the frame a sufficient distance to enable a lever, M, to be securely attached thereto. Said lever is pro-

vided with a catch, N, adapted to engage one of a series of notches, O, in a curved plate, P, thereby enabling the said crank-axle to be adjusted and retained at any desired elevation. 55

Upon the crank-axle is adjusted a metallic tube or pipe, Q, fitting loosely upon said axle.

R represents an ordinarily-constructed plow, which may be attached to the tube Q of axle F by means of a clip, S, formed of two bails, 60 T T, a plate, U, having perforations, by means of which it is fitted upon the legs of said bails and nuts V V.

The beam of the plow is adjusted longitudinally between the bails T T, which may be 65 moved laterally. A curved or recessed plate, W, is interposed between the beam and the tube Q, in order not to injure the latter, and the nuts are tightened down, thus firmly securing the plow to the crank-axle. 70

When the frame is put together for operation one of the sides A is placed with the middle hole turned down and the other in a reversed position. This will locate one of the spindles higher than the other, as shown in 75 the drawings. By shifting the position of the sides A the frame may thus be adapted to a right or left hand plow, as the case may be.

When a cultivator is to be used, the sides are both placed with the middle hole down, 80 thus adjusting the spindles and wheels at equal height.

My invention is simple, inexpensive, and easily operated, and the frame may be readily adjusted in any of the ways above mentioned. 85

Having thus described my invention, I claim and desire to secure by Letters Patent of the United States—

The herein-described improved sulky-frame, consisting of the reversible sides A A, axle D, 90 crank axle F, having lever M, foot-bar or bail L, and spindles H H, all constructed, combined, and operating substantially as and for the purpose set forth.

In testimony that I claim the foregoing as 95 my own I have hereto affixed my signature in presence of two witnesses.

BENJAMIN F. LITZENBERG.
